(57) **CLAIM**

The ornamental design for portable tool housing having elongated semi-elliptical shaped accents, as shown and described.

DESCRIPTION

FIG. 1 is a perspective view of portable tool housing having elongated semi-elliptical shaped accents according to an embodiment of the present invention;

FIG. 2 is a left side view of the portable tool housing having elongated semi-elliptical shaped accents shown in FIG. 1;

FIG. 3 is a rear elevation view of the portable tool housing having elongated semi-elliptical shaped accents shown in FIG. 1;

FIG. 4 is a right side view of the portable tool housing having elongated semi-elliptical shaped accents shown in FIG. 1;

FIG. 5 is a front elevation view of the portable tool housing having elongated semi-elliptical shaped accents shown in FIG. 1;

FIG. 6 is a top plan view of the portable tool housing having elongated semi-elliptical shaped accents shown in FIG. 1; and,

FIG. 7 is a bottom plan view of the portable tool housing having elongated semi-elliptical shaped accents shown in FIG. 1.

The broken lines in the drawing represent structure included to show the design in a condition of use and form no part of the claimed design.

The surfaces outside of the solid lines and unshaded surfaces within the solid lines form no part of the claimed design.
